BEEKMAN VAN GAASBEEK, OF MOUNT VERNON, NEW YORK.

Design No. 4,542, dated December 27, 1870.

DESIGN FOR A POULTRY-FOUNTAIN.

The Schedule referred to in these Letters Patent and making part of the same.

I, BEEKMAN VAN GAASBEEK, of Mount Vernon, in the county of Westchester and State of New York, have invented and produced an original Design for a Poultry-Fountain, of which the following is a specification.

The nature of my invention is fully represented in the accompanying drawing, which is a sectional elevation of the fountain, of which—

A is the body;

B, the drinking-basin; and
C, the funnel, to which reference is made.

I claim as my invention—

The design for a poultry-fountain, substantially as shown.

B. VAN GAASBEEK.
